UNITED STATES PATENT OFFICE.

ISADORE D. WOLFSON, OF NEW YORK, N. Y.

NECKTIE.

Application filed October 30, 1924. Serial No. 746,889.

To all whom it may concern:

Be it known that I, ISADORE D. WOLFSON, a citizen of the United States, and a resident of the city of New York, borough of Manhattan, in the county and State of New York, have invented a new and Improved Necktie, of which the following is a full, clear, and exact description.

This invention relates to neckties, an object of the invention being to provide a necktie which can be conveniently pressed.

A further object is to provide a necktie which dispenses altogether with padding, and which is composed of two thicknesses of material which may be readily ironed flat to take out wrinkles after use.

A further object is to provide a necktie composed of two thicknesses of material secured together in tubular form by lines of stitching along the edges thereof and then reversed by turning the same right side out so as to bring the seams within the tubular formation and present smooth edges.

A further object is to provide a two-ply necktie which being tubular and having closed ends confines always a certain amount of air to prevent permanent wrinkling.

A further object is to provide a necktie of this character which while having all the appearance of the ordinary necktie permits the end portions of the tie to be readily opened and laid flat so that they may be pressed in this position.

With these and other objects in view, the invention consists in certain novel features of construction and combinations and arrangements of parts which will be more fully hereinafter described and pointed out in the claims.

In the accompanying drawings—

Figure 1 is a plan view showing my improved tie completely folded, ready for use;

Figure 2 is a plan view showing the tie as it is initially made and before it is reversed or turned right side out;

Figure 3 is an exaggerated view in section on the line 3—3 of Figure 2;

Figure 4 is a view similar to Figure 3 showing the parts after the tie material is reversed;

Figure 5 is a fragmentary view showing one end of the tie open for pressing;

Figure 6 is a view showing the manner of reversing or turning the tie materials right side out.

In constructing my improved necktie I

provide suitable lengths of material which for convenience of description I shall refer to as "strips" although, of course, the tie may be made of any desired width and of any desired shape.

The outer strip 1, which constitutes that portion of the tie which is exposed when worn, may, of course, be made of silk, satin, or any other suitable material. The inner strip 2, which is normally hid from view, may be made of silk, satin or any other suitable material. These strips 1 and 2 are cut precisely alike in shape and laid one upon the other and are secured together by a line of stitching 3 which extends along both edges and around one end.

The tie thus formed is then reversed, or, in other words, turned right side out. By thus reversing or turning right side out the seam formed by the lines of stitching is enclosed and the tie presents smooth edges throughout. After the tie is turned right side out the end portions of the tie may be turned over and stitched, as shown at 4. The tie is then folded on longitudinal lines 5, 5 to give it the desired width and shape, and the intermediate portion of the tie which constitutes the neckband is permanently secured together by a line of stitching 6. The end portions of the tie where they overlap are fragilely secured so that they can be conveniently disconnected. I preferably use as a fragile securing means what is known as hand-bar-tacking, indicated by reference numeral 7, and this tacking, which is of silk or other suitable thread, can be conveniently cut so that the end portions of the tie may be laid flat, as indicated in Figure 5, to receive an iron for smoothly pressing the tie ends.

Ordinary ties are provided with padding to give them the necessary rigidity, and to maintain their shape it is practically impossible to press such ties after they are once rumpled or crinkled as the padding itself will give an uneven surface to the tie if pressed. With my improved tie I dispense altogether with the use of padding and, furthermore, I permit the tie to be opened at its ends and laid flat so that it can be conveniently pressed.

While I have illustrated a particular construction I would have it understood that I desire to claim broadly this novel construction as pertaining to neckties and the like.

Various slight changes and alterations

might be made in the general form of the parts described without departing from my invention, and hence I do not limit myself to the precise details set forth but consider myself at liberty to make such slight changes and alterations as fairly fall within the spirit and scope of the appended claims.

I claim:

- 10 1. A four-in-hand necktie composed of two thicknesses of material of substantially the same size and shape secured together at both side edges and at both ends, said tie folded upon two longitudinal fold lines extending throughout the length of the tie and said folds permanently secured to the body of the tie in the neck band portion thereof, and fragile means connecting the folds in the tying ends of the tie, said folds 20 being otherwise free in the tying ends to

permit ironing of the tying ends out flat when the fragile connecting means have been broken.

2. A four-in-hand necktie composed of two thicknesses of material of substantially 25 the same size and shape secured together at both side edges and at both ends, said tie folded upon two longitudinal fold lines extending throughout the length of the tie and said folds permanently secured to the 30 body of the tie in the neck band portion thereof, and fragile means connecting the folds in the tying ends of the tie, said folds being otherwise free in the tying ends to permit ironing of the tying ends out flat 35 when the fragile connecting means have been broken, said folds normally overlapping throughout the entire length of the tie.

ISADORE D. WOLFSON.
